FAN

Richard L. Hull, Davenport, Iowa, assignor to Ametek, Inc., a corporation of Delaware
Continuation of application Ser. No. 38,979, June 27, 1960. This application Mar. 13, 1963, Ser. No. 267,072
2 Claims. (Cl. 230—114)

The present invention relates to fan units and particularly to a new and improved split flow fan having adjustable damper means combined with it.

This application is a continuation of application Serial No. 38,979 filed June 27, 1960, and now abandoned.

In order to prevent the deterioration of a fan motor in a fan unit for moving destructive fumes or fluids, the housing for such units has been constructed in tubular form having a transverse opening therethrough that is defined by a wall that splits the flow of fluid as it passes axially through the housing. The fan motor is mounted in this transverse opening with its output shaft extending along the axial centerline of the housing and through the wall defining the transverse opening therethrough.

An object of this invention is to provide such a fan unit having a damper-like valve or vane means combined therewith for controlling the flow of fluids through the fan unit.

Another object of the invention is to provide such a fan unit in which pivotal damper, vane or valve means may be located within the unit without increasing its size.

Still another object of the invention is to provide such a fan unit in which either one or both of the split paths of fluid flow therethrough may be controlled by a damper, vane or valve means.

Still another object of the invention is to provide such a fan unit having such damper, vane or valve means in which the axis of the pivot passes through the fan motor within the transverse passage so that space limitations can be satisfied.

A still further object of the invention is to provide a fan with a valve means having improved performance as compared to a fan without such valve means.

In one aspect of the invention, a tubular housing having truncated conical ends may have diametrically disposed, elongated openings cut into the wall of said housing. Sheet metal may be connected internally of said openings, extending from one to the other and forming a wall defining a transverse passage through the housing, dividing the interior thereof to provide a split flow of fluid that may pass through said housing. This wall may include flat parallel spaced wall portions joined at the ends by curvilinear portions, thereby forming split fluid passage means having a cross-sectional form of a segment of a circle. An electric motor may be mounted within the transverse passage and may be bolted or otherwise fastened to the wall defining said transverse passage. The output shaft of the motor may extend upwardly through the wall defining the transverse passage and may have a fan fixed to it within one of the truncated end portions of the housing. Segmental vane or valve means may be located in one or both of the passages through the housing which define the split paths of fluid flow therethrough. The vane or valve means may be in the form of segments of a circle and may be located within the cylindrical portion of the housing between the truncated conical end portions, which is the location in the transverse passage in which the motor is located. Since the vane or valve means must be pivotally mounted, the pivot shaft obviously cannot extend through the housing and across the transverse passage because it would interfere with the motor within the latter.

In still another aspect of the invention, pivot means for the segmental vane or valve means may extend across

2

one or both of the split fluid passage means of segmental cross section having aligned bearings in the outer wall of the housing and one or both of the flat parallel spaced wall portions defining the transverse passage.

In still another aspect of the invention, each of these pivot means may be provided with crank means on the outside of the housing and each crank means may be capable of being locked in adjusted position.

In still another aspect of the invention, only one adjustable crank may be provided on the outside of said housing, and a linkage may be provided between a segmental vane or valve means in each of the fluid passages of segmental cross section. This linkage may include a pivot shaft extending across the transverse passage but displaced radially from the diameter of the housing on which diameter the fan motor is located.

In still another aspect of the invention, power operated means may be located within the transverse passage but displaced radially from the fan motor therein. This power operated means may be a reversible electric motor, and a crank linkage may be connected between the motor shaft and one or both of the segmental vane or valve means. Limit switches may be provided for limiting the degree of rotation of the vane or valve means motor in order to adjustably control the flow of fluid through the split passageways.

The above, other objects and novel features of the invention will become apparent from the following specification and accompanying drawings which are merely exemplary.

In the drawings:

FIG. 1 is a sectional plan view of a fan unit to which the principles of the invention have been applied;

FIG. 2 is a partial sectional elevational view of the unit disclosed in FIG. 1;

FIG. 3 is an enlarged detail of the unit shown in FIGS. 1 and 2;

FIG. 4 is a view taken along line 4—4 of FIG. 3;

FIG. 5 is a perspective view of a modified unit from that shown in FIG. 1, and to which the principles of the invention have been applied;

FIG. 6 is a partial sectional plan view of still another modified unit to which the principles of the invention have been applied; and

FIG. 7 is a view taken substantially along line 7—7 of FIG. 6.

Referring to the drawings, and particularly to FIGS. 1 to 4, inclusive, the principles of the invention are shown as applied to a fan unit including a housing 10 having a hollow cylindrical portion 11 and end portions 12 and 13 that may be in the form of hollow truncated cones. Flanges 14 and 15 may be provided at the extremities of each conical portion 12 and 13. Diametrically disposed openings may be cut in the housing 10, and in the embodiment disclosed they may have straight parallel spaced edges 16 and 17, joined at their ends by curvilinear edges 18 and 19. A sheet metal wall 20 may be fixed to the edges 16, 17, 18 and 19. Wall 20 may extend between the diametrically disposed, cut-out portions, forming therewith an hermetical seal. This construction forms a transverse passage 21 diametrically through the housing 10 and divides the interior thereof into two fluid flow passages 22 and 23 between the inlet 24 and the outlet 25 of the housing 10. Referring to FIG. 1, the two passages 22 and 23 within the cylindrical portion 11 each have a cross section that is a segment of a circle.

An electric motor 26 may be permanently attached to one of the straight parallel spaced walls 16 and 17. It may be arranged so that the axis of the output shaft 27 thereof lies along the longitudinal axis of the housing 10. The shaft 27 may extend through a clearance hole in one of the curvilinear wall portions 18 and 19, and a fan 28

may be fixed to its end, adjacent the outlet 25 of the housing 10.

In the embodiment shown in FIGS. 1 and 2, a damper-like vane or valve means 29, having a segmental shape to fit within the passage 23, may be fixed to a shaft 30 that extends across passage 23. The valve or vane means is seen to substantially fill the passage 23. Shaft 30 may be journaled in aligned bearings within the wall of housing 10 and the wall 20 fixed to the edges 17. The shaft 30 may also extend outwardly of the housing 10 and may have fixed to it a crank arm 31. A plate 32 may be attached to the outside of housing 10 and it may include an additional plate 33 having an arcuate slot 34 within which may ride a wing nut element 35 that is mounted on the arm 31.

From the foregoing it is evident that the damper-like vane or valve means 29 may be adjusted within the passage 23 to control the flow of fluid therethrough. The vane 29 is of such a length that when in open position, its upper tip will be closely adjacent the fan blades 28 so as to direct air thereto. As shown, it is longer than the axial length of the cylindrical portion 11.

Referring to FIG. 5, another segmental vane or valve means 36 may be mounted within the passage 22 of the housing 10. It may be fixed to a shaft 37 that is axially aligned with shaft 30 and is journaled in bearings within the wall of portion 11 and the wall 20. Another shaft 38, parallel with shafts 30 and 37 but displaced radially from the axis of shafts 30 and 37, may extend across the transverse passage 21 and may be journaled in bearings mounted on the parallel portions of the wall 20. Crank arms 39 and 40 may be fixed to each end of shaft 38, and the one ends of connecting links 41 and 42 may be pivotally connected to the ends of arms 39 and 40 opposite those connected to shaft 38. The opposite ends of links 41 and 42 may be pivotally connected to vane or valve means 29 and 36 by brackets 43 and 44, respectively. With the shaft 38 displaced radially from the axis of shafts 30 and 37, it is evident that the fan motor 26 can be received within transverse passage 21 along the axis of shafts 30 and 37 without interference from shaft 38. By moving crank arm 31 in a counterclockwise direction from the closed vane position as shown in FIG. 5, both vane or valve means 29 and 36 can be simultaneously adjusted to control the flow of fluid through the passages 22 and 23.

Referring to FIGS. 6 and 7, a bracket 45 may extend across the transverse passage 21 and may be fixed to the wall 20 thereof by angle members 46 and 47. A combined reversing electric motor and reduction gear unit 48 may be mounted on bracket 45. It may include an output shaft 49 extending from both ends thereof. The opposite ends of shaft 49 may extend through the parallel portions of wall 20 into the passages 22 and 23 above the vane or valve means 29 and 36. Crank arms 50 and 51 may be fixed to the opposite ends of shaft 49, and the ends of arms 50 and 51 opposite those connected to shaft 49 may be pivotally connected to links 52 and 53. The ends of links 52 and 53 opposite those connected to arms 50 and 51 may be pivotally connected to angle members 54 and 55 which latter are fixed to the vane or valve means 36 and 29, respectively. Limit switches (not shown) may be included within the circuit of the motor 48 so as to control the degree of movement of the vane or valve means by the motor 48.

Although the various features of the improved fan unit have been shown and described in detail to fully disclose several embodiments of the invention, it will be evident that changes may be made in such details and certain features may be used without others without departing from the principles of the invention.

What is claimed is:

1. In a fan unit, a housing including a hollow cylindrical portion and hollow truncated conical inlet and

outlet portions attached to said cylindrical portion; a transverse passage extending through said cylindrical portion; a wall defining said transverse passage, and forming longitudinally extending dual passages through said cylindrical portion, said wall having spaced flat parallel portions joined by curvilinear portions; motor means mounted on one of said flat parallel portions and having an output shaft extending through said wall and lying on the longitudinal axis of said housing; a fan connected to said shaft and adjacent said wall portion; vane means within at least one of said plural passages through said housing, said vane means having a straight edge extending in substantial parallelism to a flat portion of said wall and an arcuate edge which in the closed position of said vane means is disposed adjacent the inner cylindrical surface of said one passage, said vane means having an area substantially the same as the cross sectional area of said passage and the straight edge portion being longer than said cylindrical wall so as to be adjacent said fan when the vane means is in open position; pivot means in said one passage, said pivot means being fixed to said vane means and journaled in bearings in said housing and wall, said pivot means extending in a direction transverse to said vane straight edge, said vane means being located in said passage so that when said vane means is fully open it will direct air to said fan; and means for rotating said vane means.

2. In a fan unit, a housing including a hollow cylindrical portion and hollow truncated conical inlet and outlet portions attached to said cylindrical portion; a transverse passage extending through said cylindrical portion; a wall defining said transverse passage, and forming longitudinally extending dual passages through said cylindrical portion, said passages having a segmental cross section; motor means mounted within said transverse passage and substantially midway along its longitudinal axis, and having an output shaft extending through said wall into one of said truncated conical portions; a fan connected to said shaft near the extremity of one of said conical portions; segmental vane means within at least one of said segmental passages, said vane means having a straight edge extending in substantial parallelism to a flat portion of said wall and an arcuate edge which in the closed position of said vane means is disposed adjacent the inner cylindrical surface of said one passage, said vane means having an area substantially the same as the cross sectional area of said passage and the straight edge portion being longer than said cylindrical wall so as to be adjacent said fan when the vane means is in open position; pivot means in said one passage, said pivot means being fixed to said vane means and journaled in bearings in said housing and wall, said pivot means extending in a direction transverse to said vane straight edge, said vane means being located in said passage so that when said vane means is fully open it will direct air to said fan; and means for rotating said vane means.
